UNITED STATES PATENT OFFICE

WILLIAM H. WEAVER, OF VALLEY SPRINGS, CALIFORNIA

CURRENCY HOLDER

Application filed February 24, 1930. Serial No. 430,831.

My invention relates to improvements in currency holders wherein a body, shaped to fit around the arm of a wearer, is provided with an annular channel to receive currency wrapped therearound, the currency being enclosed by a sleeve detachably secured over the body to guard against loss or theft of the currency.

The primary object of my invention is to provide an improved holder for currency and the like carried upon the person of the possessor.

Another object is to provide an improved holder for currency which will effectually guard against loss or theft.

A further object is to provide an improved device of the character described wherein currency or other valuables of small bulk may be conveniently carried in concealed position, accessible to the owner when desired.

Another object is to provide an improved holder arranged to fit snugly upon the arm of a wearer and which can be removed or opened only by an intentional separation of the parts of the holder.

A still further object is to provide an improved currency holder of simple and economical construction, and which is rugged, compact, and efficient in service.

I accomplish these and other objects by means of the improved device disclosed in the drawings forming a part of the present application wherein like characters of reference are used to designate similar parts throughout the specification and drawings, and in which—

Fig. 1 is a side elevation, partly in vertical section, of my improved currency holder;

Fig. 2 is a right end elevation of the holder;

Fig. 3 is an end elevation of the body segments, shown in separated relation in full lines and in closed relation in dotted lines; and

Fig. 4 is a side elevation of the body segments in matching closed relation.

Referring to the drawings, the numeral 1 is used to designate an annular body preferably split diametrically to form a pair of matching body segments shaped to embrace

the arm of a wearer. The segments 1 are provided with grooves 2 formed upon the outer surfaces thereof, said grooves matching to form an annular channel around the body, and forming matching flanges 3 and 4 at the ends of the body segments. The segments 1 are provided with suitable alining means such as dowels 6 set upon one of the segments and detachably engaging apertures 7 formed in the opposite segment whereby the segments 6 may be rigidly held in accurate alinement.

An annular sleeve 8 is arranged to fit over the body segments 1 to hold said segments in matching relation and to cover the channel formed by the grooves 2. The sleeve is arranged to be moved axially onto the body 1 over the flange 3 at one end thereof and to form a close sliding fit with the flange 4 at the opposite end of said body, the inner edge of the flange 4 being slightly beveled, as at 9 to facilitate the movement of the sleeve 8 thereonto. The flange 3 is threaded to engage threads 11 formed upon the inner side of the sleeve 8. The sleeve 8 is preferably made of the same width as the body 1 whereby the edges of the sleeve will be flush with the ends of the body when the sleeve is moved to operative position thereon.

A securing member 12 is applied through an opening 13 formed in the sleeve 8 to engage an aperture 14 tapped into the flange 4 to secure the sleeve upon the body and to prevent the sleeve from being turned relative to the body.

In operation, the segments 1 are fitted around the arm of a wearer, the two segments being moved from opposite sides to embrace the arm, the dowels 6 being engaged by the apertures 7 to aline the segments in accurate matching relation. Currency 16, or the like, is then wound around the body 1 within the channels 2, the body 1 and channel 2 preferably being of a width adapted to receive the currency when folded once lengthwise. For convenience, a rubber band 17, or the like, is applied around the currency 16 to hold the same within the channel 2 and to also hold the segments 1 in matching relation. The sleeve 8 is then moved over the hand of the wearer and onto the matching body segments 1, the

unthreaded end of the sleeve being moved over the threaded end of the body as indicated in dotted lines in Fig. 1 of the drawings, and advanced onto the opposite flange 4. The 5 sleeve is then turned to cause the threads 11 of the sleeve to engage the threaded flange 3 of the body, thereby effectually securing the segments in operative relation, and fully enclosing the currency within the channel 2. 10 When the sleeve 8 has been advanced to match with the body 1, the securing member 12 is applied to prevent further turning of the sleeve in either direction.

The body segments 1 are of a size adapted 15 to fit snugly upon the arm of the wearer and to prevent the body from being moved over the hand of the wearer. For this purpose, the device is made in various sizes adapted to fit arms of various size. The 20 sleeve 8 being of a diameter to fit over the flanges 3 and 4 of the body 1, may be readily pressed over the hand of the wearer, thereby affording a continuous annular sleeve to hold the segments 1 rigidly in assembled relation. 25 When the sleeve 8 has been secured to the body segments 1, the assembled holder is effectually held upon the arm of the wearer. The holder may be slipped upwardly along the arm to fit with a desired snugness and to 30 be concealed within the sleeve of the wearer.

When worn in this manner, my improved holder constitutes a simple, compact and efficient means for carrying currency without fear of loss or theft, as the holder can only 35 be removed from the arm, and access had to the contents thereof, by removing the securing member 12 and unscrewing the sleeve from the body of the holder. Thus, the contents of the holder cannot be lost or stolen 40 except by force. At the same time, access may be had to the contents of the holder by the wearer without serious inconvenience.

The body 1 and sleeve 8 are preferably formed from aluminum, though other materials 45 may be substituted if desired. The exterior of the sleeve is polished or finished in any desired manner. The inner surface of the body 1 is preferably provided with a knurled portion 18 adjacent one end of 50 the body whereby the body may be caused to grip the arm while the sleeve 8 is being applied or removed. The knurling also provides a surface to which a lining, not shown, may be applied if desired.

55 While I have illustrated and described only one embodiment of my invention, the device is, of course, subject to modification in numerous ways without departing from the spirit of my invention. I therefore do 60 not wish to restrict myself to the specific details of construction and arrangement illustrated and described, but desire to avail myself of all modifications which may fall within the scope of the appended claims.

65 Having thus described my invention, what

I claim as new and desire to secure by Letters Patent is:—

1. A currency holder comprising a split body member formed of matching segments and shaped to fit around the arm of a wearer, 70 said body having an annular channel formed upon the outer surface thereof to receive currency wrapped therearound; and a sleeve detachably engaging the body to secure the body portions in matching relation around the arm and to enclose the currency within the annular channel. 75

2. A currency holder comprising a split body member formed of matching segments 80 shaped to fit around the arm of a wearer, said body having an annular channel formed upon the outer surface thereof to receive currency wrapped therearound; a sleeve detachably engaging the body to secure the segments in matching relation around the 85 arm and to enclose the currency within the channel; and means for securing the sleeve over said channel to enclose the contents thereof.

3. A currency holder comprising a split 90 body formed from matching segments shaped to fit around the arm of a wearer and having matching grooves forming an annular channel around the body to receive currency wrapped therearound; and an annular sleeve 95 movable axially onto the body from one end thereof to secure the segments in matching relation and to enclose the currency within the channel.

4. A currency holder comprising a split 100 body formed from matching segments shaped to fit around the arm of a wearer and having matched grooves forming an annular channel around the body to receive currency wrapped therearound; and an annular sleeve 105 movable axially onto the body from one end thereof to secure the segments in matching relation and to enclose the currency within the channel, said sleeve being threaded at one end thereof to engage corresponding threads formed upon the body segments. 110

5. A currency holder comprising a split 115 body formed from matching segments shaped to fit around the arm of a wearer and having matching grooves forming an annular channel around the body to receive currency wrapped therearound; an annular sleeve movable axially onto the body from one end thereof to secure the segments in matching relation and to enclose the currency within the channel, said sleeve being threaded at one end thereof to engage corresponding threads formed upon the body segments; and means 120 engaging the sleeve and body to secure the sleeve in operative position and prevent inadvertent removal of said sleeve. 125

6. A currency holder comprising a split body formed from matching segments shaped to fit around the arm of a wearer and having matching grooves forming an annular chan- 130

- nel around the body to receive currency wrapped therearound; means carried by the segments for alining said segments in matching relation; and an annular sleeve movable axially onto the body from one end thereof to enclose the currency within the channel and provided with threads engaging corresponding threads formed upon the body to secure the sleeve upon the body.
- 10 7. A currency holder comprising a split body formed from matching segments shaped to fit around the arm of a wearer and having matching grooves formed thereon to form an annular channel around the body to receive currency wrapped therearound; dowels engaging adjacent segments to aline the same in matching relation; and an annular sleeve movable axially onto the body to enclose the currency within the channel, said sleeve being provided with threads engaging corresponding threads formed upon the body to secure the sleeve upon the body and to hold the segments in matching assembled relation around the arm of the wearer.
- 15 8. A currency holder comprising a split body formed from matching segments shaped to fit around the arm of a wearer and having matching grooves formed thereon to form an annular channel around the body to receive currency wrapped therearound; dowels engaging adjacent segments to aline the same in matching relation; an annular sleeve movable axially onto the body to enclose the currency within the channel, said sleeve being provided with threads engaging corresponding threads formed upon the body to secure the sleeve upon the body and to hold the segments in matching assembled relation around the arm of the wearer; and means
- 20 40 for securing the sleeve against turning relative to the body.
9. A currency holder comprising a split body formed from matching segments shaped to fit around the arm of a wearer and having matching grooves formed thereon to form an annular channel around the body to receive currency wrapped therearound; dowels engaging adjacent segments to aline the same in matching relation; an annular sleeve
- 25 45 movable axially onto the body to enclose the currency within the channel, said sleeve being provided with threads engaging corresponding threads formed upon the body to secure the sleeve upon the body and to hold the segments in matching assembled relation around the arm of the wearer; and a screw detachably engaging the body through an aperture formed in the sleeve to secure the sleeve against turning relative to the body.
- 50 55 60 In witness whereof, I hereunto set my signature.

WILLIAM H. WEAVER.
